UNITED STATES PATENT OFFICE

2,471,036

RUNNING ROPE LUBRICATOR

Wesley R. Jenkins, Whiting, Ind., assignor to
 Carnegie-Illinois Steel Corporation, a corpora-
 tion of New Jersey

Application February 21, 1945, Serial No. 579,109

3 Claims. (Cl. 184—17)

1

This invention is concerned with the problem of lubricating a running rope, particularly a wire rope, the object being to provide a means for lubricating such a rope without stopping its running and without involving the inefficiency and hazard incidental to the manual application of a lubricant.

The accompanying drawings illustrate a specific example of the invention in a combination effecting lubrication of the rope powering the skip of an iron smelting blast furnace skip hoist, this combination eliminating the inefficiency and hazard formerly connected with the manual lubrication of this running rope. The various figures are as follows:

Figure 1 shows a side view of this example including only the pertinent parts of the furnace and hoist.

Figure 2 shows an enlarged side view of the novel portion of Figure 1;

Figure 3 is a partly sectioned top view of Figure 2; and

Figure 4 is an enlarged section taken from Figure 2 as shown there by the line IV—IV.

More specifically, these drawings show the blast furnace top platform 1, the upper portion of the skip hoist incline 2 and the skip hoist rope 3 which powers the skip and runs over the sheave 4 at the skip hoist top, all of which is familiar to those who know about blast furnaces. The top platform 1 is high above the ground and is a hazardous place to work, particularly since it is on top of the blast furnace, and heretofore lubrication of the rope 3 has required that a workman stand on the platform 1 and manually apply the lubricant to the rope 3 with the inefficiency attendant all manual work.

According to this invention, a retractable mount 5 is positioned near the skip hoist top and mounts a sheave wheel 6 for its peripheral tangential contact with the rope 3 and for its retraction therefrom, means being provided for supplying lubricant to the periphery of this wheel 6 and other means being provided for operating the mount 5 from near the skip hoist bottom during skip hoist operation to effect the described contact and retraction of the wheel respecting the rope. This arrangement provides for lubrication of the running rope 3 whenever this is required by causing the wheel to contact the rope, and this can be done without stopping the operation of the skip hoist and without necessitating anyone climbing to the platform 1 of the blast furnace. The lubricant is efficiently applied to the rope and no hazard is involved.

2

The mount 5 comprises horizontally spaced lever arms 7 journaled for free vertical swinging on a horizontal shaft 8, this shaft 8 being keyed to a lever block 9 working vertically between the arms 7 and having horizontally and rigidly projecting pins 10 riding arcuate slots 11 formed in the sides of the arms 7 with the shaft 8 as their common axis, the shaft 8 being itself journaled to the skip hoist frame for free rotative movement and provided with an operating lever 12 worked vertically by a rope 13 going down to the skip hoist bottom. With this arrangement, pulling on the rope 13 pulls down on the lever 12 which turns the shaft 8 so as to lift the block 9 which, through the operation of its pins 10 working to the upper limits of the slots 11 of the arms 7, lifts the arms 7 and throws the wheel 6 clear from the rope. Release of the rope 13 permits the wheel 6 to fall into contact with the rope 3, its connection with the shaft 8 through the medium of the pins 10 projecting from the block 9 and working in the slots 11 in the arms 7, providing a lost-motion connection permitting the wheel 6 to rise and fall with the working of the running rope 3, by reason of the permissible rise and fall of the arms 7 within the limits of slots 11 and pins 10, whereby the wheel 6 always contacts the rope 3.

The wheel 6 is journaled on an axle 14 non-rotatively positioned by the arms 7 by means of keeper plates 15 attached to the arms 7 by cap screws 16 and engaging recesses in the sides of the axle 14. This axle 14 has an axially extending duct 17 opening at one of its ends where it is provided with a lubricant supply line connection 18, this axle also having at least one radially extending duct 19 opening at its side between its ends and communicating with the axially extending duct 17. The wheel 6, that is rotatively journaled by this axle 14, has a circumferentially grooved periphery 6a for engaging the rope 3 and is provided with a number of radially extending ducts 20 opening inside the grooved periphery 6a and also opening to the axle-side-opening of the radially extending duct 19 in the axle 14 during rotation of the wheel 6 thereon. The wheel rides the axle on longitudinally spaced plain bearings 21 and its central inside portion is provided with a circumferential recess 22 which registers with the previously mentioned opening of the duct 19, the bearings being spaced at the recess. The axle has other axially extending ducts 23 leading to the sliding surfaces of the axle 14 and bearings 21 by way of radially extending ducts 24 in the axle, these ducts 23 opening at the opposite end

of the axle 14 from the connection 18 and being provided with lubricant-pressure-gun fittings 25.

The above described assembly provides the means for furnishing the periphery of the wheel 6 with lubricant, the lubricant being introduced under pressure through a flexible line to the connection 18, flowing through the duct 17 and duct 19 to the circumferential recess 22 from which it flows through the ducts 20 to the grooved periphery 6a. This lubricant may be a special lubricant particularly designed for use on the rope 3, it being excluded from the sliding surfaces between the bearings 21 and the axle 14 by means of seals 26 which are on either side of the recess 22 between it and the inner ends of the spaced bearings. The provision of the ducts 23 and 24 permits the sending of a separate lubricant to the bearing surfaces of the axle 14 and bearings 21, which is especially designed for use there, the seals 26 also functioning to confine this lubricant to where it belongs.

Although not previously mentioned, a blast furnace skip hoist is sometimes provided with dual ropes arranged close together, it being for such a reason that the grooved periphery 6a is shaped as illustrated. However, the same principles would apply when a single rope is involved excepting that the contour would be different in an obvious manner. Also, there is usually a pair of skip hoists arranged in parallel relation for each blast furnace, and in such instances the wheel assembly that has been disclosed herein may be used in multiple as required, it being possible to use the same shaft 8 to mount the other wheel assembly.

Undue loss of the lubricant is prevented by a shield or fender 27 which is arranged to closely embrace the periphery and sides of the wheel 6 excepting for that portion which must be exposed to work on the rope 3. This shield is carried by the arms 7 so as to move synchronously with swinging of the wheel.

I claim:

1. In a running rope lubricator including a shaft journaled in spaced bearings, a pair of lever arms spaced along said shaft and rotatable thereon, an axle extending between said arms, and a sheave wheel journaled on said axle, said axle and wheel having lubricant-supply passages therein, the improvement comprising a lost-motion connection between the shaft and said levers including a member rigid with said shaft and engageable with the levers, whereby the wheel when in engagement with the rope, is free to float and accommodate itself to movements of the rope transversely of its direction of travel.
15. 2. Apparatus as defined by claim 1 characterized by said member having a pin-and-slot connection with at least one of said levers.
20. 3. Apparatus as defined by claim 1 characterized by said levers having slots therein intermediate their ends, said member being a block between said levers having pins projecting into said slots.

WESLEY R. JENKINS.
